No. 792,212.

PATENTED JUNE 13, 1905.

R. HEDDLE.
PROTRACTOR GAGE.
APPLICATION FILED APR. 3, 1905.

UNITED STATES PATENT OFFICE.

ROBERT HEDDLE, OF NELSON, CANADA.

PROTRACTOR-GAGE.

SPECIFICATION forming part of Letters Patent No. 792,212, dated June 13, 1905.

Application filed April 3, 1905. Serial No. 253,601.

To all whom it may concern:

Be it known that I, ROBERT HEDDLE, a subject of the King of Great Britain, residing at Nelson, in the county of Kootenay, Dominion 5 of Canada, have invented certain new and useful Improvements in Protractor-Gages; and I do declare the following to be a full, clear, and exact description of the invention, such as will enable others skilled in the art to which it app- 10 pertains to make and use the same.

This invention relates to protractor-gages, and the principal object of the same is to provide a protractor attachment to be applied to an ordinary steel square and which can be 15 readily adjusted for finding angles, diagonals for laying out stairs, circles, polygons, triangles, and other geometric figures.

Another object is to provide a device of this character which can be quickly and accurately 20 adjusted at different points upon opposite sides of an ordinary steel square to provide a gage for the purposes referred to.

These and other objects are attained by means of the construction illustrated in the 25 accompanying drawings, in which—

Figure 1 is a plan view of a protractor-gage made in accordance with my invention and applied to an ordinary steel square. Fig. 2 is an edge view of the same. Fig. 3 is a plan 30 view of the protractor-gage when used to lay out angles; and Fig. 4 is a detail sectional view, taken through one end of the gage-bars and through the fastening-screw for securing said device together at opposite sides of the 35 square.

Referring to the drawings for a more particular description of my invention, the numeral 1 denotes an ordinary steel square, having upon its opposite faces the usual scale- 40 marks 2, one side being divided into sixteenths and the other side into twelfths of an inch, as is the usual practice. The gage-bars 3 are each provided with an opening 4 at each side of its pivotal point 5, and upon the face 45 of the bar adjacent to the openings is a scale or centering mark 6. These bars are provided with right-angular flanges 7, also provided with scale-marks 8, which correspond with the scale-marks upon the opposite sides

of the square 1. At the ends of said bars 50 binding-screws 9 are provided, a stud 10 rising from one of said bars and properly threaded to accommodate the nuts 11. A spring 12 is disposed between the two gage-bars and fingers 13 project upward from the lower bar 55 through apertures 14 at the ends of the spring and through holes 15 in the upper gage-bar. By this means the plates are spaced apart to compensate for the thickness of the steel 60 square.

A sector-shaped gage-plate 16, provided with a scale 17 and a straight base portion 18, which lies against one edge of the square, is provided with a pivot 19, which passes through both gage-bars and through said plate. Said 65 pivot 19 comprises a square shank upon one member and a threaded thumb-screw passing through the opposite member and into the square portion of said screw to hold the parts in proper relative positions. 70

From the foregoing it will be obvious that my invention may be applied to an ordinary steel square and adjusted to the required positions for laying out and determining many geometrical problems. When used as shown 75 in Fig. 3, the device may be used for laying out angles, as will be readily understood.

Various changes in the form, proportion, and the minor details of construction may be resorted to without departing from the principle or sacrificing any of the advantages of 80 this invention.

Having thus described my invention, what I claim as new, and desire to secure by Letters Patent, is—

1. A protractor-gage for attachment to a steel square comprising gage-bars provided with sight-openings, angularly-bent flanges and a sector-shaped gage-plate pivoted between said bars, substantially as described. 85 90

2. A protractor-gage comprising parallel bars, each having oppositely-disposed sight-openings provided with scales, a gage-plate pivoted between said bars and provided with a curved scale and set-screws for holding said 95 gage-bars upon opposite sides of a steel square.

3. A protractor-gage comprising parallel bars, an intermediate gage-plate provided

2
with a curved scale and pivoted between said bars, means for clamping said gage-plate at any adjusted position, set-screws at the ends of said bars, spring-spacers between said bars and fingers projecting from one of said bars through apertures in the other bar, substantially as described.

In testimony whereof I have hereunto set my hand in presence of two subscribing witnesses.

ROBERT HEDDLE.

Witnesses:

E. H. STANLEY,
JAMES HARGREAVES.
